UNITED STATES PATENT OFFICE.

FRANK C. MISH, OF GREENVILLE, VIRGINIA.

CONCRETE AND STEEL SPRING RAIL TIE.

Application filed May 10, 1928. Serial No. 276,621.

The present invention relates to improvements in rail ties and has for its principal object to provide a tie that includes a concrete base, and a spring steel rail supporting plate arranged on the concrete base in spaced relation thereto, means being provided for positively anchoring the rails on the upper face of the steel plate so that spreading of the rails will be prevented.

10 Another important object of the invention is to provide a rail tie of the above mentioned character which is simple in construction, inexpensive, strong and durable and further well adapted to the purpose for which it is designed.

15 Other objects and advantages of the invention will become apparent from the following description when taken in connection with the accompanying drawing.

20 In the accompanying drawing wherein like reference characters indicate corresponding parts throughout the same:—

Figure 1 is a side elevation of the rail tie embodying my invention showing the manner 25 in which a pair of rails are supported and secured on the upper face of the spring steel plate.

Figure 2 is a top plan view partly in section and

30 Figure 3 is a vertical section taken on the line 3—3 of Figure 1 for more clearly showing the inverted U-shaped member.

In the drawing wherein for the purpose of illustration is shown the preferred embodiment of my invention, the numeral 1 designates the concrete base of the tie that is of substantially rectangular shape. A spring steel plate 2 of the same dimensions as the concrete base 1 is adapted for disposition on top of the base in spaced relation thereto, and to this end, a pair of rollers or pins 3 extend transversely between the inner opposed faces of the base and plate. A washer 4 is disposed on each end of each pin for disposition against the adjacent side of the concrete base and the steel plate 2, and a cotter pin 5 extends through an opening formed in the outer ends of each pin to properly retain the pins against displacement.

50 The upper face of the spring steel plate 2 is formed with the transversely extending cut out portion 6, 6 adjacent the respective ends thereof to receive the base of the rails 7. The intermediate portion of the top face of the steel plate 2 is further formed with a transverse cut out portion to receive the crown 8

of a substantially inverted U-shaped member, the arms thereof being disposed downwardly on opposite sides of the steel plate and the concrete base as shown at 9 in Figure 3. The free end of each arm is bent laterally as at 10, and thence upwardly as at 11 to form the opposed saddles 12. The purpose of these saddles will be hereinafter more fully described.

The rail securing means will now be specifically described. A sleeve 13 is disposed within a transverse opening formed in the concrete base 1 directly below each rail 7 and extending through each sleeve is the elongated pin 14, the ends of the each pin projecting beyond the respective sides of the concrete base. A pair of bars 15 are disposed on opposite sides of the concrete base in diagonally opposed relation, and each of these bars is bent intermediate its ends to form an upwardly directed portion 16, the free end of which is disposed inwardly as shown at 17 to engage with the base of the adjacent rail. These bars have their bight portions 18 disposed around the respective pins 14 at the outer ends thereof and a washer 19 is placed over the respective pins at one end thereof for engagement with the bight portions of the bars. A cotter pin 20 extends transversely through an opening formed in each end of each pin so that said bars will be prevented from sliding off of the ends of the respective transversely disposed pins.

Cooperating with the bars 15 are additional bars 21, the same being disposed on opposite sides of the tie and in diagonally opposed relation. The outer end portion of each bar 21 is curved as at 22 to provide a pin engaging portion, and the end portion of each bar extends upwardly at an incline as at 23, and the laterally disposed foot 24 is formed on the upper end thereof for engagement with the base portion of the respective rails at the inner edge thereof, as indicated very clearly in Figures 1 and 2 of the drawing.

The inner end portion of each of the bars 21 is adapted for rest upon the respective saddles 12, and as is shown very clearly in Figures 1 and 2, the inner extremity of each bar 21 terminates in a threaded cylindrical portion 25.

A turn buckle 26 is swivelly connected at one end to the inner end of each bar 15, while the other end is formed with a threaded opening to receive the threaded inner end of the respective bar 21 and manifestly by actuating the turn buckle, the bars 15 and 21 on each

side of the tie may be adjusted toward or away from each other.

Additional washers 19 are arranged on the other ends of the transverse pins around 5 which the curved portions 22 of the bars 21 extend and additional cotter pins 20 extend through these particular ends of the pins to retain the washers and the bar 21 in position.

Normally the parts are arranged as shown 10 in Figure 1, and the spring steel plate 2 that supports the rails 7 will be properly spaced with respect to the concrete base 1, and the hooked upper ends of the bars will firmly engage 15 with the inner and outer edge portions of the base flanges of the rails to positively secure the rails on the spring steel plates.

Under certain circumstances, where a 20 heavy load is placed on one of the rails, this particular end of the steel plate will flex downwardly, but the saddle carrying member will cooperate with the inner connected bars to at all times maintain the hooks or feet 17 and 24 in engagement with the base flanges of the rails so that said rails cannot be 25 displaced from their recesses seats 6 formed in the upper face of the steel plate, and when the load is taken off of the flexed end of the spring steel plate, said spring steel plate will 30 return to its initial horizontal position. It is of course understood that when the end of the bar 2 is depressed, the middle portion with the saddle is raised to avoid loosening of the bars about the pins 14.

It will thus be seen from the foregoing 35 description that I have provided a rail tie that will be strong and durable, and at the same time prevent spreading of the rails.

Furthermore, the tie can be readily and 40 easily assembled or disassembled whenever necessary.

While I have shown the preferred embodiment of my invention, it is to be understood 45 that minor changes in the size, shape and arrangement of parts may be resorted to without departing from the spirit of the invention, or the scope of the appended claims.

Having thus described the invention, what 50 I claim as new and desire to secure by Letters Patent is:—

- 50 1. In a rail tie, a plastic base, a spring steel plate for disposition on top of the plastic base in spaced relation thereto, rails arranged transversely across the upper face of the steel plate, means for securing the rails against movement independently of the steel plate, said means including a substantially inverted U-shaped member arranged over the intermediate portion of the steel plate and the base, saddles formed on the free ends of the arms of the inverted U-shaped member, pins 55 projecting transversely through the concrete base beneath the respective rails, rods arranged on opposite sides of the plastic base, the outer end portions of the rods being bent 60 for disposition around the respective ends 65 of the pins, laterally disposed base flange engaging feet formed on the upper end of the upwardly bent outer ends of the rods, the intermediate portions of the rods being adapted 70 for rest within the respective saddles.
- 75 2. In a rail tie, a concrete base, a spring steel plate for disposition above the concrete base, pins extending transversely between the opposed faces of the concrete base and the spring steel plate to space said plate with respect to the base, a pair of rails arranged transversely across the upper face of the spring steel plate adjacent the respective ends thereof, a substantially inverted U-shaped member straddling the intermediate portion 80 of the spring steel plate, saddles formed on the free ends of the arms of said inverted U-shaped member, a pair of bars arranged on each side of the concrete base, means for adjustably securing the inner ends of each pair 85 of bars together, the outer ends of the bars being bent upwardly for disposition adjacent the sides of the spring steel plate, pins extending transversely through the concrete base beneath the respective rails, the bight 90 portions of the bars being disposed around the respective ends of the pins, base flange engaging feet formed on the upper ends of the upwardly disposed portions of said bars, said 95 saddles adapted to support the adjacent portions of the respective bars.
- 100 3. In a rail tie, a concrete base, a spring steel plate for disposition above the concrete base, pins extending transversely between the opposed faces of the concrete base and the spring steel plate to space said plate with respect to the base, a pair of rails arranged transversely across the upper face of the spring steel plate adjacent the respective ends thereof, a substantially inverted U-shaped member straddling the intermediate portion 105 of the spring steel plate, saddles formed on the free ends of the arms of said inverted U-shaped member, a pair of bars arranged on each side of the concrete base, means for adjustably securing the inner ends of each pair 110 of bars together, the outer ends of the bars being bent upwardly for disposition adjacent the sides of the spring steel plate, pins extending transversely through the concrete base beneath the respective rails, the bight portions of the bars being disposed around the respective ends of the pins, base flange engaging feet formed on the upper ends of the upwardly disposed portions of said bars, said 115 saddles adapted to support the adjacent portions of the respective bars, the aforementioned adjusting means including a turn buckle swivelly connected to the inner end of one bar on each side of the tie, the inner end 120 of the complementary bar being formed with a threaded portion for threaded engagement with the turn buckle.
- 125 4. In testimony whereof I affix my signature.

FRANK C. MISH.
